UNITED STATES PATENT OFFICE

RUSSELL G. CORY, OF MONTCLAIR, AND WALTER M. CORY, OF MAHWAH, NEW JERSEY

INDUSTRIAL ELEVATOR ARRANGEMENT

Application filed October 12, 1929, Serial No. 399,196. Renewed August 6, 1932.

Our invention relates to new and improved constructions or arrangements of buildings, usually of the type of warehouses or factory buildings, and of elevators for such buildings, and especially elevators designed to handle goods trucks with increased efficiency. The general purpose of the invention is to enable motor trucks to be moved on elevators to the various floors of the building and conveniently run off of the elevators to convenient adjacent positions on each floor where they may be unloaded or loaded, and then run back upon the elevator and lowered for exit from the building; and especially to enable these truck movements to be made to and from relatively restricted areas of each floor, such areas usually including a plurality of distinct truck spaces adjacent each elevator, so that there is a minimum provision of floor space for truck manoeuvring.

In certain preferred forms, the invention provides the desired elevator and truck space construction or arrangement in connection with truck landing floors or platforms located below the main floor levels, on the general plan disclosed in our prior application, Serial No. 321,748, filed November 24th, 1928; but this is not essential in all cases and when desired, the truck landing spaces may be arranged on the main floor levels in proper relation to the elevator or elevators.

The invention includes special plan forms or contours of elevator cars or car frames (usually called "slings"), designed to provide space economy and to give the desired truck manoeuvring facility, with or without a cab mounted in the sling for independent motion and especially for a horizontal, lateral, swinging or pivotal motion, to reposition the motor truck after it has been run into the cab, for the delivery of the truck to a desired position or space on the building floor.

The characteristics and advantages of the invention are further sufficiently explained in connection with the following detail description of the accompanying drawings, which show representative embodiments. After considering these examples, skilled persons will understand that many variations may be made without departing from the

principles disclosed and we contemplate the employment of any structures that are properly within the scope of the appended claims.

Fig. 1 is a plan view of a part of a warehouse or similar building, and elevator structure or arrangement, embodying the invention in one form. 55

Fig. 2 is a similar view, enlarged, of the elevator and shaft and adjacent truck landing floors or areas. 60

Fig. 3 is a vertical section at 3—3, Fig. 2.

Fig. 4 is a view similar to Fig. 2, of a modified arrangement.

Figs. 5, 6 and 7 show other modified arrangements. 65

In Figs. 1, we illustrate in plan a portion of a factory, warehouse or similar building in which a motor truck elevator is located. We show a single elevator and cooperative construction or arrangement of adjacent part of the building structure involved, but evidently, the elevators and other structural features may be arranged in groups in "batteries." One important purpose of the invention is to provide for the handling of a relatively large number of trucks to and from a plurality of economically arranged landing spaces or stalls on each floor, so that the carrying capacity of a single elevator may be fully utilized and that it may also at the same time conveniently and rapidly deliver trucks to and remove them selectively from a plurality of landing spaces on each of the various floors. 70 75 80

The elevator car 10 conventionally illustrated in Fig. 1, is in one form as shown, of the special plan form which we conveniently designate for descriptive purposes as "hour glass" form. That is, it includes a central portion 11 which is only moderately wider than the over-all width of a standard motor truck, and end portions 12 which have an outwardly flaring or diverging form as defined by the side edges 13. As otherwise described, the elevator car proper or the outside outlines of its frame, has flaring ends leading from a relatively narrow or restricted waist portion, at 11. The area indicated by horizontal surface shade lines in Fig. 1 may represent the floor of the elevator car upon which the motor 85 90 95 100

truck may be run directly in any of several positions, as will appear. This is better illustrated in Fig. 4 where 10a is an elevator car floor of the same shape as that shown in Fig. 5 1 without any independent or movable cab mounted on the floor or in the elevator sling. As shown in Fig. 1 and also in Figs. 2 and 3, in some preferred cases, we mount movably in the sling an independently movable car or 10 cab 15. The movement of this cab is in a horizontal plane and usually it has a swinging movement, on a center which may be at the center of the elevator car, as in Figs. 1, 2 and 3, or otherwise located, as will appear. 15 In Figs. 1, 2 and 3 the cab 15 is mounted on a center or pivot bearing 16 and has under the end portions 12 wheels or rolls 17 supporting and guiding the end portions of the cab on rails 18 on the elevator sling 10, so that the 20 cab swings horizontally on its center as a pivot. Desirably, the ends of the elevator car or the cab 15 are arcuate as at 20, Fig. 1 for the greatest space economy.

The hour-glass or waist form of the elevator car provides room for the necessary vertical guide rails 21 to be located at the waist portions of the car without making the overall width-wise dimension of the elevator shaft, as indicated by its side walls 22, any greater 25 than the greatest lateral width of the elevator car or cab frame structure, and at the same time provides for necessary motor truck movements, as will appear.

Adjacent one or preferably both ends of the 30 elevator car, any or all of the building floors, one of which is illustrated in Fig. 1, has one or a plurality of truck receiving spaces 23. When the motor trucks are to be run off the elevator onto the building floor at the main 35 floor level, these truck spaces need not be definitely defined. The side walls 24 shown in Fig. 1 however define the maximum space needed on the main or a sub-floor of the building to receive two trucks to be handled to and 40 from one end of a single elevator car. In one preferred form of the invention, for reasons fully explained in the above identified application, that is especially to facilitate the rapid handling of trucks and goods to and from the 45 trucks by unloading on a floor surface level with the truck floor, the truck spaces 23 of Fig. 1 consist of pits or depressed or sub-floors, otherwise herein called landing floors, 50 Fig. 3. These floors are depressed as 55 shown in Fig. 3, a distance below the main floor level 26 equal to the distance from the treads of the motor truck wheels to the average truck floor level, so that when the trucks are backed into the pits 25, goods may be 60 moved to and from the truck floors with maximum convenience. In this case, the side walls 24 of Fig. 1 together with the rear walls 27 define the limits of the pits, each of which is dimensioned to receive a standard motor 65 truck. The distinct pits 25a and 25b angu-

larly and divergently arranged, as shown in Fig. 1 need not be separated by any central walls (as will later be referred to) but in one preferred arrangement as shown in that figure, where only two definite spaces such as 25a 70 and 25b are provided for trucks at one or each end of the elevator car, angularly arranged central walls 28 and may be provided, defining the inner limits of each pit; and the space between the pits may be utilized as a shaft 29 75 for pipes or any other desired fittings extending vertically through the building.

When an independent truck cab is mounted in the sling as in Figs. 1, 2 and 3, the cab is preferably provided with side walls such as 30 forming complete side enclosures for the cab, and the elevator controlling mechanism and the operator are located or stationed within the cab, so that it is unnecessary and in fact impossible for the operator to stand 80 on the sling or any floor which might be placed thereon, and risk of injury to the operator by swinging of the cab is therefore obviated; also since the motor truck in the 85 cab need have only a straight line motion in relation to the cab, there is little risk of injury to the operator by contact with the motor truck as it moves in or out.

In structure as illustrated in Figs. 1 to 3, when the elevator is at the ground floor level, 90 the cab 15 may be swung to any desired angular position, in relation to the elevator car proper, to receive a motor truck which may be run upon it from any convenient position 95 on the ground floor. The truck may be run 100 forward or backward into the cab, usually forward, and the only care in regard to the position of the truck in the cab is with reference to the end of the cab from which the truck is to be run at an upper floor since the 105 truck must be backed off of the cab in order to properly locate it in a truck space such as 23, and especially to back its tail end up against the rear wall 27 of a landing pit, 110 when the pit arrangement is used. When the 115 elevator is moved to any floor at which there is a vacant car space at the proper end of the elevator, the cab 15 is swung to align a truck with that space, and the truck is then backed straight off into the space.

With the described arrangement it is unnecessary when the truck is placed in the cab, to previously determine which of the spaces such as 23 on any floor is vacant for truck reception, since the cab may be swung 120 to properly position the truck for movement into any of the spaces when the floor is reached.

The above described hour glass or similar plan form of the elevator car or cab and generally corresponding or divergent arrangement of the truck spaces such as 23 provides additional space economy in the building 125 since other facilities, such as the ordinary freight or passenger elevators such as 35 may 130

be arranged in a curved row formation at one side of the elevator shaft and truck spaces, this row of elevator shafts being incurved into the space provided by the stated truck elevator shaft and truck space arrangement and providing floor or passage space of increased width as at 36 adjacent the central portion of the row of service elevators. Similarly at the other side of the truck elevator and truck space arrangement, general facilities for the building such as toilet rooms at 37 and locker rooms 38, office elevators 39, etc., may be arranged to realize full space economy.

Fig. 4 shows an arrangement similar to that of Fig. 1, with omission of the movably mounted cab. In this instance, the area 10a represents the contour of the elevator floor. Trucks must be run upon the elevator in positions which have reference to the location of the vacant truck space on one or another of the upper floors. Evidently when the motor truck is run on the elevator in an angular position corresponding to any one of the vacant spaces on a floor it may easily be backed off into that space without any lateral or twining moving whatever. The waist or hour glass form of the elevator car permits such angular positioning of the motor truck with an over-all width of the central or waist portion of the car which is very slightly greater than the over-all width of the truck.

Fig. 5 shows a modification in which the elevator car floor or sling frame 10b is of generally triangular form as defined by its side edges 40. This arrangement also may be used with or without an independent cab 41. When such cab is provided, it will in this case be pivotally mounted at one end of the elevator car proper, as at 42. Guide rails for the elevator car are provided at intermediate points of the sides at 43. In this arrangement, two or more, or specifically as shown, three truck spaces 23a, 23b and 23c are provided at one (the wider) end of the elevator, and a single car space 23d is provided at the other, narrow end. When there is no swinging cab on the elevator car, the truck may be properly positioned in the act of running it upon the elevator car floor 10b so that it may be backed off into either of the spaces 23a, 23b, or 23c, at the wide end of the elevator, or into the single space 23d at the other end; or if a movable cab 41 is provided, the truck may be positioned when it reaches any floor to be backed into any of the vacant spaces.

Fig. 6 sufficiently shows a modification of the hour glass elevator arrangement in which the car floor or frame 10c is made in outwardly diverging curved or bell form in either direction from the central or waist portion 11. When a cab such as 15a is provided, it may be pivotally mounted at the center of the car as in Fig. 1, and the sides 30a of the cab may be of approximately correspond-

ing curved or bell shape, as shown. This arrangement gives greater facility for truck manoeuvring, since the curved side walls of the elevator car or cab permit the front end of the motor truck to swing as it backed off from 70 or run forward upon the car floor or into the cab. The floor areas provided adjacent the shaft for reception of the trucks may therefore be of smaller total lateral area than would otherwise be possible. Thus, 75 space is provided at each end of the elevator car or cab sufficient to receive three trucks side by side as sufficiently indicated by the dot and dash lines 50, and the side walls of the pit 51 or other lateral limits of the truck 80 receiving space may also be curved in their parts adjacent the elevator shaft as indicated at 52 to allow for some swinging of the front end of the truck as it is backed into or run forward away from either of the side spaces 85 on the floor. This arrangement also illustrates the provision of at least three truck spaces at each end of the elevator car, so that by the proper positioning of the motor truck on the elevator car floor, it may be run into 90 any one of the three spaces; and when the central space on any floor is not occupied by a truck, the truck may be backed into it or either of the side spaces which may be vacant without reference to its previous positioning on the elevator. Of course, when a separate swinging cab is used, the cab may be swung as in previous examples, to discharge a motor truck into any space that may be vacant regardless of what other ones are 95 100 or are not occupied.

Fig. 7 illustrates another arrangement in which a relatively large number of truck spaces or pit spaces may be provided at either or both ends of an elevator car or cab. In 105 this case, the car floor plan and cab arrangement, may be similar to that of Fig. 1. At either or both ends of the car or cab, the available floor space for trucks is defined by the lines or walls 60 and 61 and these 110 lines in turn define car spaces or slips as at 62, 63 and 64, in angular arrangement at either side of a central space or aisle 65, as defined by the dot and dash lines. This central aisle may lead to a rear central truck 115 slip or space 66. Evidently, if the floor area between the lines 60, 61, etc. is depressed, providing a depressed landing as in Fig. 3, the stated lines represent walls which are 120 the limits of the entire pit area. By this arrangement, a relatively large number of trucks may be located in the various floor or pit spaces such as 62, 63, 66, etc. and after leaving the elevator, the trucks may be backed into any space without interfering with trucks in the other spaces, by reason of the central aisle 65. In fact, this arrangement provides considerable space for truck manoeuvring in the truck or pit space at 130

either end of the elevator, with relatively moderate total area of such spaces.

It is practically necessary for considerations of safety to provide adequate doors at the elevator shaft. We provide such doors in leaf form, each of the leaves such as 70 and 71 of Fig. 2 for example being of horizontal sectional shape corresponding to the shaft and elevator car form; that is, when the ends of the car or cab are arcuate, the door leaves are correspondingly curved or arcuate. Each leaf is substantially of truck width and the leaves are mounted in guides to slide horizontally, so that either leaf may be pushed to one side to overlap the other and permit movement of a truck to and from the elevator and to or from any of the landing spaces. When more than two landing spaces are provided, say three, as in Fig. 5 or Fig. 6, for example, the doors will of course, consist of three leaves as 70, 71 and 72 and in such cases it is only necessary that two of them shall have an overlapping relation although of course all three leaves may be made to overlap so that all may be placed in overlapping relation to permit two-thirds of the width of the end of the elevator car to be accessible for truck movements to and from the car or corresponding floor spaces.

30 By any of the described arrangements, a single elevator may be used up to approximately its full capacity to serve a number of floors, each of which may have a plurality of truck landing spaces. Various additional 35 modifications of the structure or arrangements shown will be apparent to skilled persons, without further detailed explanation.

We claim:

1. In a building of the class described, 40 having a plurality of floors, a truck elevator serving the various floors, and having a fixed floor dimensioned with minimum total horizontal area to receive a truck in any of several angular positions, and restricted truck 45 landing spaces on various of the floors at one end of the elevator and dimensioned to receive trucks in various positions in substantial alignment with their positions on the elevator.

50 2. In a building of the class described, having a plurality of floors, a truck elevator serving the various floors, and having a fixed floor dimensioned with minimum total horizontal area to receive a truck in any of several 55 angular positions, and restricted truck landing spaces on various of the floors at both ends of the elevator and dimensioned to receive trucks in various positions in substantial alignment with their positions on the elevator.

60 3. In a building of the class described, having a plurality of floors, a truck elevator serving the various floors, and having a fixed floor dimensioned with minimum total horizontal area to receive a truck in any of sev-

eral angular positions, and restricted truck landing spaces on various of the floors at one end of the elevator and dimensioned to receive trucks in various positions in substantial alignment with their positions on the elevator, said restricted landing spaces consisting of landing floors located at levels below the main floor levels so as to position trucks floors substantially at the main floor levels.

70 4. In a building of the class described, having a plurality of floors, a truck elevator serving the various floors, and dimensioned with minimum total horizontal area to receive a truck in any of several angular positions, and restricted truck landing spaces on various of the floors at one end of the elevator and dimensioned to receive trucks in various positions in substantial alignment with their positions on the elevator, and a cab independently mounted in the elevator sling for limited lateral movement to selectively position a truck in relation to landing spaces on the building floors.

75 5. In a building of the class described, having a plurality of floors, a truck elevator serving the various floors, and dimensioned with minimum total horizontal area to receive a truck in any of several angular positions, and restricted truck landing spaces on various of the floors at one end of the elevator and dimensioned to receive trucks in various positions in substantial alignment with their positions on the elevator, and a cab independently mounted in the elevator sling for limited lateral movement to selectively position a truck in relation to landing spaces on the building floors, the cab having 80 protecting side walls and being dimensioned to accommodate the elevator operator and controlling mechanism.

85 6. In a building of the class described, having a plurality of floors, a truck elevator serving the various floors, and dimensioned with minimum total horizontal area to receive a truck in any of several angular positions, and restricted truck landing spaces on various of the floors at one end of the elevator and dimensioned to receive trucks in various 90 positions in substantial alignment with their positions on the elevator, and a substantially enclosed truck cab pivotally mounted on the elevator sling for limited movement.

100 7. In a building of the class described, having a plurality of floors, a truck elevator serving the various floors, and having a fixed floor dimensioned with minimum total horizontal area to receive a truck in any of several angular positions, and restricted truck landing spaces on various of the floors at one end of the elevator and dimensioned to receive trucks in various positions in substantial alignment with their positions on the elevator, said truck spaces on the floors being 105 110 115 120 125 130

arranged to receive at least two trucks in angularly diverging position.

8. A building structure comprising a plurality of floors, a truck elevator shaft, and a car therein serving the floors, the car being of substantial hour-glass plan form to receive a truck in any of several different angular positions, and restricted truck landing spaces on several of the floors at one end of the elevator car and providing in substantially minimum area for parking a plurality of trucks.

9. A building structure comprising a plurality of floors, a truck elevator shaft, and a car therein serving the floors, the car being of substantial hour-glass plan form to receive a truck in any of several different angular positions, and restricted truck landing spaces on several of the floors at one end of the elevator car and providing in substantially minimum area for parking a plurality of trucks, and a cab pivotally mounted in the car sling and of approximate hour-glass form in plan.

10. A building structure comprising a plurality of floors, a truck elevator shaft, and a car therein serving the floors, the car being of substantial hour-glass plan form to receive a truck in any of several different angular positions, and restricted truck landing spaces on several of the floors at one end of the elevator car and providing in substantially minimum area for parking a plurality of trucks, and additional building facilities such as elevators occupying available space at the sides of the elevator car or shaft and truck landing spaces and provided by the generally centrally convergent form of such shaft and spaces.

11. A building structure comprising a plurality of floors, a truck elevator shaft, and a car therein serving the floors, the car being of substantial hour-glass plan form to receive a truck in any of several different angular positions, and restricted truck landing spaces on several of the floors at both ends of the elevator car and providing in substantial minimum area for parking a plurality of trucks in angular positions substantially corresponding to their positions when on the elevator car.

12. A building structure comprising a plurality of floors, a truck elevator shaft, and a car therein serving the floors, the car being of substantial hour-glass plan form to receive a truck in any of several different angular positions, and restricted truck landing spaces on several of the floors at both ends of the elevator car and providing in substantial minimum area for parking a plurality of trucks in angular positions substantially corresponding to their positions when on the elevator car, and a cab pivotally mounted in the car sling and of approximate hour-glass form in plan.

13. A building structure comprising a plu-

rality of floors, a truck elevator shaft, and a car therein serving the floors, the car being of substantial hour-glass plan form to receive a truck in any of several different angular positions, and restricted truck landing spaces on several of the floors at both ends of the elevator car and providing in substantial minimum area for parking a plurality of trucks in angular positions substantially corresponding to their positions when on the elevator car, and additional building facilities such as elevators occupying available space at the sides of the elevator car or shaft and truck landing spaces and provided by the generally centrally convergent form of such shaft and spaces.

14. In a building of the class described, having a plurality of floors, a truck elevator serving the various floors, and having a fixed floor dimensioned to receive a truck in any of several angular positions with minimum total horizontal area, and restricted truck landing spaces on various of the floors at one end of the elevator and dimensioned to receive trucks in various positions in substantial alignment with their positions on the elevator, and elevator shaft doors at the building floors having a plurality of independently horizontally movable overlapping leaves, each leaf being of width substantially corresponding to truck width and allowing for movement of the truck to and from the elevator and to and from any of the landing spaces.

15. In a building of the class described, having a plurality of floors, a truck elevator serving the various floors, and having a fixed floor dimensioned to receive a truck in any of several angular positions with minimum total horizontal area, and restricted truck landing spaces on various of the floors at one end of the elevator and dimensioned to receive trucks in various positions in substantial alignment with their positions on the elevator, the ends of the elevator car and adjacent building floor edges being generally arcuate, and leaf doors on the floors adjacent the shaft or elevator car, the leaves being substantially of truck width, arcuate, and slidably mounted for horizontal movement to admit passage of the truck to and from the elevator or car or cab and to and from any of the landing spaces.

16. In a building of the class described, having a plurality of floors, a truck elevator serving the various floors, and dimensioned to receive a truck in any of several angular positions with minimum total horizontal area, and restricted truck landing spaces on various of the floors at one end of the elevator and dimensioned to receive trucks in various positions in substantial alignment with their positions on the elevator, and a cab independently mounted in the elevator sling for limited lateral movement to selectively

- position a truck in relation to landing spaces on the building floors, the ends of the elevator car or cab and adjacent building floor edges being generally arcuate, and leaf doors
- 5 on the floors adjacent the shaft or elevator car, the leaves being substantially of truck width and slidably mounted for horizontal movement to admit passage of the truck to and from the elevator or car or cab and to
- 10 and from any of the landing spaces.
17. A building structure comprising a plurality of floors, a truck elevator shaft, and a car therein serving the floors, the car being of substantial hour-glass plan form to receive a truck in any of several different angular positions, and restricted truck landing spaces on several of the floors at one end of the elevator car and providing in substantially minimum area for parking a plurality of trucks, and a cab pivotally mounted in the sling.
18. A building structure comprising a plurality of floors, a truck elevator shaft, and a car therein serving the floors, the car being of substantial hour-glass plan form to receive a truck in any of several different angular positions, and restricted truck landing spaces on several of the floors at both ends of the elevator car and providing in substantial minimum area for parking a plurality of trucks in angular positions substantially corresponding to their positions when on the elevator car, and a cab pivotally mounted in the sling.
19. In combination, a building having a plurality of floors, an elevator shaft, an elevator mounted in the shaft and adapted to carry vehicles to the floors, the base of the elevator being formed with one open end wider than the average width of the vehicles, said elevator base converging inwardly from the widened end.
20. In combination, a building having a plurality of floors, an elevator shaft, an elevator mounted in the shaft and adapted to carry vehicles to the floors, the base of the elevator being formed with a restricted middle portion wide enough to accommodate a vehicle, the elevator diverging outwardly from the restricted portion toward the entrance and exit ends, thereby permitting the elevator to receive and discharge vehicles in directions at angles to the center line of the elevator passing through the entrance and exit ends.
21. In combination, a building having a plurality of floors, an elevator shaft, an elevator mounted in the shaft and adapted to carry vehicles to the floors, the base of the elevator being formed with a restricted middle portion wide enough to accommodate a vehicle, the elevator diverging outwardly from the restricted portion toward the entrance and exit ends, and a depressed truck
- landing pit adjacent at least one end of the elevator.
- In testimony whereof we affix our signatures.
